UNITED STATES PATENT OFFICE.

PATRICK BAKER, OF TORONTO, ONTARIO, CANADA.

WAISTCOAT.

SPECIFICATION forming part of Letters Patent No. 316,220, dated April 21, 1885.

Application filed March 14, 1884. (No model.)

To all whom it may concern:

Be it known that I, PATRICK BAKER, of the city of Toronto, in the county of York, in the Province of Ontario, Canada, gentleman, have invented certain new and useful Improvements in the Manufacture of Under-Garments; and I do hereby declare that the following is a full, clear, and exact description of the same.

10 The object of the invention is to produce an under-garment from material of flexible texture and yet impervious to air; and it consists, essentially, of a composition composed of paper-pulp mixed with jute or other fibrous 15 material in such proportions as shall produce a material of flexible texture and yet impervious to air.

10 In a climate where the human frame is subjected to the sudden changes of temperature 20 such as we suffer from in Canada and portions of the United States an under-garment made from material which is impervious to air, and yet which is as flexible as an ordinary cotton shirt, will be appreciated by all 25 who are subjected to the discomforts of the sudden changes mentioned.

30 The drawing represents a view of a waistcoat made from the flexible impervious material herein referred to. This material is produced substantially in the same manner as ordinary paper, except that the paper-pulp before being rolled into sheets has mixed with it a quantity of jute or other fibrous material, the said jute being mixed in about the proportion of one-half jute to one-half paper-pulp, and is so mixed that it forms an integral part of the entire material when rolled between the cylinders used in the manufacture of paper. In order that the material 35 thus produced shall be flexible, care must be taken that no resin or other sizing shall in any way be added; but in every other respect, except the addition of the jute to the paper-pulp and the dispensing with the sizing, my 40 improved material is made exactly in the same manner as ordinary paper, and when finished is cut into the required shapes to form the particular garments it is intended to produce. For instance, in the drawing I exhibit a waist-

50 coat, A, composed of the impervious paper described, and having its edges B bound with cotton, silk, satin, or other similar material, so as to protect the said edges and prevent the garment being torn. It will be noticed that all the edges are thus protected, and that 55 the buttons C are attached to the waistcoat A by a thread passing through the impervious paper and through tape or other similar textile, D, sewed onto the inside of the waistcoat. These strips D serve as strengthening-strips, 60 and prevent the garment being torn out by strain on the buttons or the loops E, by which they are fastened. The loops E pass through the impervious material, and are secured in any convenient way to the strengthening- 65 strip D.

Other garments besides waistcoats may also be made in the same manner, the points to be observed in their manufacture being that all the edges shall be protected by the binding 70 described, and that the buttons sewed onto the impervious material shall be firmly fixed thereto by tape or other similar textile.

What I claim as my invention is—

1. As a new article of manufacture, a waistcoat, A, or other garment made from a composition of paper-pulp and jute or other fibrous material, as specified, and having its edges B bound and provided with a strengthening-strip, D, to which the buttons C are secured, 75 substantially in the manner specified.

2. The waistcoat herein described, made from an impervious flexible material composed of paper-pulp and jute or other fibrous material, as specified, and having its edges 80 bound and provided with the strengthening-strips D, secured to the inside thereof, the buttons C, secured to one of said strips, and the loops E, passing through the impervious material and fastened to the other strengthening-strip, substantially as herein shown and described.

Toronto, March 5, 1884.

P. BAKER.

In presence of—

GEO. W. BOOMER,
CHARLES C. BALDWIN.
